INVENTOR,
Edward Dick,
BY *Harry W. Brown*
ATTORNEY.

UNITED STATES PATENT OFFICE.

EDWARD DICK, OF SPRINGFIELD, MASSACHUSETTS, ASSIGNOR TO NATIONAL BLANK BOOK COMPANY, OF HOLYOKE, MASSACHUSETTS.

LOOSE-LEAF DOUBLE POCKET.

Application filed February 10, 1920. Serial No. 357,618.

To all whom it may concern:

Be it known that I, EDWARD DICK, citizen of the United States of America, residing in Springfield, county of Hampden, and Commonwealth of Massachusetts, have invented certain new and useful Loose-Leaf Double Pockets, of which the following is a specification.

This improvement relates to improvements in loose leaf sheets for use in loose leaf binders, and having pockets on the opposite sides or faces thereof, whereby as the sheet is turned in the binder from one side to the other, the pockets are rendered accessible for readily placing articles therein and removing them therefrom. Heretofore it has been a common practice to have portfolios in which the leaves are permanently attached to the binder element of the book, or that portion of the book which fixedly secures the leaves in place. The present invention is designed to be limited for use in connection with a loose leaf binder, whereby the leaves may be readily inserted or removed therefrom as desired. It possesses the advantage of having a pocket on the opposite faces for the purpose of increasing the volume or number of letters or other papers that may be inserted in the pockets. These detachable leaves are sometimes spoken of as fly leaves or guard sheets.

Referring to the drawings forming a part of the specification:

Fig. 1 is a plan view of one of the leaves detached from the binder, showing a pocket on one side or face thereof, and the eyelets therein which are located at one edge through which the rings of the binder pass.

Fig. 2 is a vertical sectional view on the line 2—2 of Fig. 1, showing the fly or guard leaf with the pockets secured to the opposite sides of the same.

Fig. 3 is a perspective view showing one of the leaves inserted in the binder and letters or other papers inserted in one of the pockets. Fig. 4 illustrates the use of a smaller leaf.

Referring to the drawings in detail: The body, or main portion of the fly or guard leaf is indicated at 1, which may be composed of any suitable flexible material, as leather or leatherette, and having eyelets or openings, 2, in one border thereof for receiving the rings of the binder. Stitched

or otherwise suitably secured to the lower part of the opposite faces of the fly or guard leaf 1 are pieces 3 and 4, preferably of the same material as the guard leaf, indicated at 1, the stitching or securing means being indicated at 5. The outer upper inclined edges, 6, of the pocket pieces extend to substantially one half of the length of the leaf, and as shown, the pockets are slightly distended to illustrate the receiving openings 7. As shown in Fig. 3, papers are inserted in one of the pockets indicated at 4, the papers being designated by the numeral 8. It is of course obvious that these pockets may be used for inserting papers of like nature, as bills receivable, receipts, etc., and that when the leaf or sheet 1 is turned over on the rings 9, the opposite face of the sheet is exposed and the pocket on that side of the sheet can be used for similar articles, thus increasing the volume of matter that may be filed by the use of a single sheet or leaf having pockets on its opposite faces.

It is obvious that these leaves may be removed and filed away with their contents, and other fly or guard leaves inserted or substituted in their place. It is also obvious that these leaves may be of different sizes for insertion in a book of pocket size, or they may be made larger for office use, without departing from the spirit and scope of the invention. The improvement is one that can be readily constructed of inexpensive material as it possesses few parts and they can be readily stitched together, and the pockets secured by any suitable means.

It should be observed that the arrangement of the pockets at the lower portion of the sheet is such that the letters are inserted in a vertical position, thereby enabling the observer to read the titles without it being necessary to turn the book around into different positions.

Referring to Fig. 4, it will be seen that the pockets with their inclined upper entrance edge instead of extending upwardly substantially one half of the length of the sheet as shown in Figs. 1, 2 and 3, are formed as shown at 3² with its inclined entrance edge 3² located lower down on the sheet 1, as shown to permit the letters or other papers to be readily inserted or removed, and also to enable them to be bent over across the edge 3² for the purpose of

examination. This structure permits papers of different lengths to be inserted in the same pocket.

It is of course obvious that the pockets shown in Fig. 4 may extend different distances across the face of the sheet 1 to suit the convenience of the user.

The opposite ends of the inclined edge 3² are spaced away from the lower edge of sheet 1 as shown.

What I claim is:

1. A single unfolded sheet for loose leaf binders, said sheet having a pocket piece of separate material secured on each of the opposite sides of the sheet by stitching along three of its edges and each piece being formed with an inclined entrance edge which extends from the edge that is attached to the binder to its free or outer edge of the

sheet, the opposite extreme ends of the inclined edge of said piece being spaced from the lower end of the leaf, as shown and described, to permit the pockets on the opposite sides of the leaf to receive and file papers of different lengths, and to permit the ends 25 of the filed papers to project above the inclined edge.

2. A sheet for loose leaf binders comprising a single unfolded member formed with openings to receive the rings of the binder, 30 said member having separate pieces which are secured on the opposite sides thereof by stitches and along three of its edges to provide pockets and their other edges being inclined to form the receiving edges of the 35 pockets.

EDWARD DICK.
